UNITED STATES PATENT OFFICE.

PETER COOPER HEWITT, OF RINGWOOD MANOR, NEW JERSEY.

FLYING-MACHINE.

1,378,114.

Specification of Letters Patent.

Patented May 17, 1921.

Application filed June 14, 1919. Serial No. 304,192.

To all whom it may concern:

Be it known that I, PETER COOPER HEWITT, a citizen of the United States, and a resident of Ringwood Manor, in the county of Passaic and State of New Jersey, have invented certain new and useful Improvements in Flying-Machines, of which the following is a specification.

My invention relates to flying machines and more particularly to flying machines of the type known as helicopters in which the machine is lifted by the action of one or more propellers rotating about a vertical or upright axis.

15 The general object of the invention is to provide an improved machine of this type; but many of the features are not limited to such machines.

Another object of the invention is to provide an efficient helicopter of compact and strong construction and of light weight.

Another object of the invention is to provide an improved propeller construction, suitable for a helicopter, in which blades of any desired improved form, even if very thin, may be used without sacrificing the strength of the propeller or the efficiency of the blades.

Other objects, features and advantages of 30 my invention will appear more fully in the following detailed description and the appended claims.

The accompanying drawings forming part 35 of this specification illustrate one embodiment of my invention.

In the drawings; Figure 1 is a side elevation of said embodiment of my invention, part of the fuselage being broken away.

Fig. 2 is a top plan view thereof.

40 Fig. 3 is a section taken on line 3—3 of Fig. 1.

Fig. 4 is an end view on an enlarged scale of a portion of the landing device.

Fig. 5 is a detail plan view of another 45 portion of the landing device.

Fig. 6 is a detail plan view, on a scale larger than Fig. 1, of one of the propeller arms.

Fig. 7 is a vertical sectional view taken 50 on line 7—7 of Fig. 6.

Fig. 8 is a cross section taken on line 8—8 of Fig. 7.

Fig. 9 is an elevation on an enlarged scale 55 of an end portion of one of the wires used in the construction shown.

The helicopter shown comprises an upper propeller 1 and a propeller 2 below the same, the propeller 1 being carried by a normally vertical shaft 3 which passes through the tubular shaft 4 of the propeller 60 2. The shaft 4 extends through a stationary tubular bearing 5 forming part of the frame 6 of the machine, and stationary with respect thereto. This frame carries a fuse-
lage 7.

65 The shafts 3 and 4 and the propellers carried thereby are driven in opposite directions by motors or engines 8 and 9 of equal power arranged one to the front and the other to the rear of the shafts 3 and 4, and having their driving shafts arranged in axial alignment longitudinally of the fuselage 7, the axis of said driving shafts intersecting the axis of the shafts 3 and 4 at right angles. The shaft of the engine or 75 motor 8 is provided with a beveled pinion 10, and the shaft of the motor 9 with the beveled pinion 11. Each of these pinions meshes with a beveled gear 12 secured to the shaft 4 above the pinion, and also with the 80 beveled gear 14 secured to the shaft 3 below the pinion.

The arrangement shown is such that a balanced action is obtained in driving the shafts 3 and 4, and there is substantially no 85 lateral thrust on the various bearings inasmuch as each moving part of the mechanism is acted upon by equal forces acting in opposite directions. Each of the gears 12 and 14, for example, is acted upon on one side 90 of its axis by the pinion 10, tending to drive the same in one direction, for example forwardly, referring to Fig. 1, while on the other side of its axis it is acted upon by the pinion 11, tending to drive the same with 95 equal force in the opposite direction, or rearwardly in the case assumed. In other words, a true dynamic couple is obtained, causing rotation with little or no lateral thrust upon the bearings, with the motors 100 exercising equal power. The driving means for the propellers are claimed in another application filed on even date herewith, and a further description thereof is thought to be unnecessary herein.

105 Each of the propellers, as shown, comprises two blades 16 and 17 arranged on opposite sides of the axis of the propeller shafts 3 and 4. The blades of each propeller are supported by a rigid truss secured 110

midway between its ends to the corresponding propeller shaft. Each of the trusses, as shown, comprises a substantially horizontal compression member 19 extending radially from the propeller shaft and a compression member 20 extending from the corresponding propeller shaft in the same vertical plane as the member 19. The members 19 and 20 are connected by struts 21; and wires or tension members 22, 23 extend diagonally across the spaces between each pair of adjacent struts and the compression members 19, 20. As shown, the blades 16, 17 perform the function of the members 19 as compression members of the truss throughout substantially the whole length of said blades. The blades, however, desirably terminate at their inner ends a distance from the axis of the propeller at least one-fifth the radius of the propeller and preferably a greater distance.

The struts 21 are arranged at gradually diminishing distances apart from the axis of the propellers to the outer ends of the propeller arms and the compression members 20 are inclined so as to approach the members 19 and the propeller blades gradually more closely toward the outer ends of said arms. As shown in Fig. 2, the struts 21 and the compression members 20 are consecutively of diminishing cross section from the inner toward the outer ends of the propeller arms. The construction is, therefore, such that the trusses have the greatest strength at their inner ends where the total load thereon is greatest.

The truss structure or supporting means for each blade projects from the blade along only one of the faces thereof; and, as shown, the whole truss construction is arranged in the space below the blades of the upper propeller and above the blades of the lower propeller. By reason of this construction the length of the propeller shafts between the upper end of the upper propeller and the lower end of the lower propeller may be made relatively short with the result that the weight of the propeller shafts may be made correspondingly small and the machine correspondingly light and compact. The fuselage may, with this construction, be brought up close to the lower propeller blades; and as a result, tilting of the machine for horizontal or lateral flight may be very easily accomplished.

Referring to Fig. 3, it will be seen that the propeller blades have in cross section the shape of an aeroform aeroplane wing. Such wings have been the subject of considerable study and many of the improved wing shapes, known in the art as aeroform shapes, or aerofoils, are shown and discussed in various publications including the authoritative book by Eiffel entitled: "The Resistance of the Air and Aviation." Such shapes have upper and lower surfaces (or forward and

rear surfaces considering the direction of thrust on the shape) of different contour in cross section; and it has been found that the lifting effect on the upper surface is greater than that on the lower surface. The wing shape shown is shape No. 32 in said book. By reason of the construction shown, very thin blades may be employed, inasmuch as it is not necessary to construct the blades so that they have sufficient strength within themselves to enable them to support themselves in proper relation to the propeller shaft, the truss affording a structure external to or without the blades of very great strength. A propeller of this construction, because of the possibility of employing propeller blades of most efficient aeroform shape, is very efficient, even where the truss members are made of considerable cross sectional area to afford the requisite strength; this being especially true when the truss members are made of stream line shape.

The propeller blade is supported so that the center of the support of the blade transversely to its length is forwardly of the center of pressure upon the blade. The location of the center of pressure of lift depends upon various factors, including the shape of the blade and the pitch angle or angle of incidence thereof, and may be a substantial distance forwardly of the center of the blade. For a blade of the shape shown and supported as shown, the center of pressure will be between the longitudinal center line of the blade and the axes of the struts 21, and closer to the latter than to the former. In other words, the center of support transversely of the blade is forwardly of the center of pressure or lift and desirably not more than about 30% of the width of the blade rearwardly from the front edge thereof. As a result, the blade is pulled around by the supporting arm instead of being pushed, danger of chattering is obviated. The mounting of the propeller blades so as to accomplish these results is claimed broadly in another application filed on even date herewith.

The various parts of the truss passing through the air and encountering air resistance, other than the wings or blades 16, 17, are of stream line shape. This includes the members 19, 20, as clearly shown in Fig. 8, as well as the struts 21, as shown in Fig. 6, and desirably also the wires or tension members 22, 23. The truss construction shown supports the propeller blades rigidly in position with respect to the propeller shafts in either direction vertically or parallel to the axis of the propeller shafts. Furthermore, by properly proportioning the width of the trusses, the latter are able, without additional means, to transmit the torsion of the propeller shafts to the propeller blades without bending the trusses in

a horizontal direction. The use of truss members having a stream line shape tends to strengthen the trusses against such bending.

In Figs. 6 to 9 inclusive I have shown 5 means whereby the various truss members are connected to each other. As shown in Fig. 7, the body portion of the member 19 is made in sections, each section extending between a pair of adjacent struts 21. The various sections of said member are connected together by means of brackets 25, which are each provided with a strip 26 extending longitudinally of the truss and desirably seated at opposite ends within adjacent sections 15 of the member 19 so that the upper surface of said strip will lie flush with the upper surface of said member, as clearly shown in Fig. 8. The body portions of members 19 and 20 and the struts 21 are, as shown, made 20 of wood and the brackets 25 of a light metal, such as aluminum. Each bracket 25 is secured to adjacent ends of the wooden sections of the member 19 by means such as rivets 27, which pass through the strips 26, 25 the wooden sections of members 19 and strips 28 of metal, such as aluminum, fitting within the lower portions of said sections of the member 19 flush therewith. The upper ends of the wires 22, 23, are secured within 30 tubular projections 29, 30, of the brackets 25 by means which will be more fully described hereinafter. Each bracket 25 is secured, as by a rivet 31, to the upper end of the strut 21, the lower end of the strut being secured to a bracket 32, which is provided with strip-like extensions 33, 34. These extensions are secured, as by rivets 35, to the member 20 of the truss. The rivets 35, as shown, pass through projections 33, 40 34, the wooden body portions 36 of member 20 and a strip 37 of metal, such as aluminum, extending longitudinally of the said member and having its lower surface flush with the member 20 and desirably curved in accordance with the stream line shape of the said member. As shown in Fig. 7, the plate 37 and the bracket 32, both of which are desirably made of light metal, such as aluminum, are directly connected by a screw 45 38. The lower ends of adjacent wires 22, 23, are connected with the brackets 32, as will be hereinafter more fully described.

In a propeller such as that shown the stress upon the wires 22, 23, is very great 55 and this is especially true with large propellers for lifting heavy loads. The wires or tension members 22, 23, are accordingly made of a very strong material such as steel. If these wires were threaded directly into 60 the brackets 25 and 32 the loads or stresses transmitted through the threads would be very large and greater than practical where the brackets 25 and 32 are made of material, such as aluminum, which has insufficient 65 strength for taking such a strain, it being

understood that the wires 22, 23 are of relatively small cross sectional area and the threads thereof relatively shallow. I obviate this objection by the provision of a threaded connection whereby the wires may 70 be connected to the brackets without applying to the threads of the latter an excessive stress per unit of area.

To the above end, the upper ends of the wires, as shown, are threaded respectively 75 into nuts or sleeves 40. These nuts have peripheries which are threaded into the projections 29 or 30 of the brackets 25, the nuts 40 being desirably made of a strong metal, such as steel. The intermeshing threads of 80 the wires and the nuts being made of strong material are able to stand, without deformation, the loads or stresses thereon. The threaded area between the nuts or sleeves and the brackets is of considerably larger 85 diameter than, and of approximately the same length, as the threaded area between the wires and the nuts or sleeves; so that the total threaded area between the nuts or sleeves and the brackets is very much larger 90 than the total threaded area between the nuts or sleeves and the wires. Accordingly, the stress per unit area over the former area is smaller than the stress per unit area over the latter area. Satisfactory results may be 95 obtained with the parts substantially in the proportion shown for the particular construction herein described, the outer diameter of the nut being approximately three times the inner diameter thereof. The nuts 100 as shown are provided with openings 41 by which they may be rotated by means of a suitable tool.

I find that best results are obtained by the use of a thread substantially of the shape 105 shown in Fig. 9 in which the weak outer ends of the usual V thread, as well as the sharp inner ends of the spaces between such threads are omitted, the sides of the thread being, however, inclined as with such V 110 threads. With this construction not only are the weak portions of the threads omitted, but at the same time the threads are not cut so deep into the wire as to unnecessarily reduce the strength thereof. This 115 construction, accordingly, retains the most effective portions of the threads with the minimum weakening of the wire.

The lower ends of the wires, as shown, have mounted thereon disks 42, the peripheries of which are threaded into the bracket 32. The disks 42 are freely rotatable about the wires. The wires are provided at their lower ends with enlargements 44 engaging the lower faces of the disks and transmitting thereto the stresses in the wires when the wires are put under tension. The enlargements 44 are made of sufficient size and strength to be capable of transmitting the stress to the disks 42 without deformation 120 125 130

or other damage to either wire or disks; and the disks 42, which are made of strong metal, such as steel, have a periphery of a diameter materially larger than that of the adjacent end of the wire. By making the diameter and thickness of the disks 42 of suitable size the stress per unit area between the disks and the brackets 32 may be brought within practical working limits. By reason of the fact that the disks 42 are rotatable on the wires 22, 23, they may be threaded into position without objectionable twisting of the wires before the latter are under tension and after said wires have been firmly anchored at their upper ends. It is to be noted that in the construction shown the fastening means for both ends of the wires are located within the compression members of the truss and do not offer objectionable resistance to the rotation of the propellers.

The landing device shown herein is in the nature of a stand affording a base of considerable size by which the machine may be supported in upright position. The device, as shown, comprises a plurality of legs pivotally supported from the frame of the machine and arranged to be positioned below the fuselage for supporting machine or to be folded into close proximity to each other and lifted into operative position where they offer no objectionable resistance to the movement of the machine. In the drawings three legs are shown, a forward leg 50 and two rear legs 51 and 52 respectively. The leg 50 is mounted to swing about its axis 53 in a vertical plane while the legs 51, and 52, as clearly shown in Fig. 4, are arranged to swing without their axes 54 and 55 respectively, in planes inclined downwardly and outwardly with respect to the plane in which the leg 50 moves. As shown in Figs. 1 and 4, the pivot of the leg 50 is arranged below the pivots of the legs 51 and 52 so that when the legs are moved upwardly to inoperative position, as shown in dot and dash lines in Fig. 1, the leg 50 may be arranged below the legs 51 and 52. It will be seen that when the legs 51 and 52 are arranged in inoperative position, as shown in dot and dash line in Fig. 1, their longitudinal axes will be parallel with each other and with the longitudinal axis of the leg 50 so that the legs will lie in very close relationship with each other; whereas when the legs are lowered to operative position, as shown by solid line in Fig. 1, the legs 51 and 52, as well as the leg 50, will have been inclined downwardly and away from each other so that their lower ends will be a substantial distance apart. The legs 50, 51, 52, accordingly, when in operative position form a tripod, the lower ends of which are a considerable distance apart so as to be capable of securely holding the machine in an upright position.

For limiting the movement of the lower ends of legs 50, 51, 52, away from each other braces 56, 57 and 58 are provided, the brace 56 being pivoted at its outer end to the leg 50 adjacent to the lower end of the latter and 70 the braces 57 and 58 being pivoted at their outer ends to the legs 51 and 52 respectively by pin and slot connection 59, shown in Fig. 1. The inner ends of the brace members 56, 57 and 58 are connected with each other, as 75 by a universal joint 60, as shown in plan in Fig. 5, the pin and slot connection 59 permitting collapsing of the tripod to the position shown in dotted line in Fig. 1, while permitting the location of the pivots 54 and 55 at a 80 higher level than the pivot 53.

For collapsing the toggle formed by the brace members 56, 57, 58, so that the legs may be moved downwardly toward each other to the position shown in dotted lines 85 in Fig. 1, a wire or cable 61 is connected, as shown, to the member 60, this wire extending over a guide roll 62 to suitable means, such as the drum 63 for winding up or letting out the said wire. Suitable means 90 are also provided for drawing the legs upwardly to inoperative position after they have been collapsed to the position shown in dotted lines in Fig. 1. These means, as shown, comprise a wire or cable 65 connected to the leg 50 and extending over a guide roll 66 in the bottom of the fuselage to winding mechanism, such as the drum 67. The leg 50 may be provided with suitable means such as projections 68 on opposite sides 100 thereof for engaging the legs 51 and 52 to insure the lifting of the latter when the leg 50 is lifted to inoperative position. Suitable means are also provided to insure the movement of the leg 50 outwardly into 105 proper operative position. These means, as shown, comprise a wire or cable 70 connected with the leg 50 adjacent to the lower end thereof and extending over a guide roll 71 in the bottom of the fuselage to suitable 110 winding mechanism, such as the drum 72, within the fuselage.

When it is desired to move the landing device from operative position to inoperative position the drum 72 is rotated to release the wire or cable 70, whereupon the drum 63 is rotated to wind up the wire or cable 62 to break the toggle 56, 57, 58, and permit the legs to move downwardly by gravity to the position shown in the dotted lines in Fig. 1. The drum 67 is then rotated to wind up the wire or cable 65 and move the legs into inoperative position, as shown in dotted and dash lines in Fig. 1. The fuselage may be provided with an opening or recess in the bottom to receive the landing device, or the major portion of the latter, as shown, when the landing device is moved to inoperative position. Each of the drums is, of course, provided with suit- 130

able retaining mechanism which may be of any desired and well known construction.

When it is desired to move the landing device to operative position, the drum 67 is rotated to release the wire or cable 65, whereupon the legs drop to the dotted position shown in Fig. 1. Upon the rotation of the drum 63 to release the wire or cable 62, the toggle tends to fall downwardly to operative position by gravity and to move the legs member to operative position. To insure movement of the legs to such position the wire or cable 70 is wound upon the drum 72.

15 Any suitable steering means may be used in connection with the helicopter shown, such, for example, as the steering means shown in my co-pending application, Serial No. 304,190, filed by me on even date here-with. A description of such means is thought to be unnecessary for a clear understanding of the invention and is accordingly omitted for simplicity and clearness.

It is to be understood that many of the 25 features of this invention, although shown in connection with a helicopter, are not limited to such a machine. It is also to be understood that while I have shown one embodiment of my invention I am not limited 30 to this embodiment and that many modifications may be made in the construction shown without departing from my invention.

Having thus described my invention, what 35 I claim as new and desire to secure by Letters Patent, is:

1. The combination of two propellers and means for supporting the same for rotation about a common axis, said propellers being spaced apart along said axis and comprising blades and members supporting said blades and arranged entirely within the space between the blades of the respective propellers.

45 2. The combination of two propellers and means for supporting the same for rotation about a common axis, said propellers being spaced apart along said axis and comprising blades and truss members supporting said blades and arranged entirely within the space between the blades of the respective propellers.

55 3. The combination of two propellers, means for supporting the same for rotation about a common axis, said propellers being spaced apart along said axis and comprising blades and truss members supporting said blades and arranged entirely within the space between the blades of the respective propellers, and driving means for said propellers arranged outside of said space.

60 4. The combination of two propellers, means for supporting the same for rotation about a common axis, said propellers being

spaced apart along said axis and comprising 65 blades and truss members supporting said blades and arranged entirely within the space between the blades of the respective propellers, said members co-acting with said blades for supporting the same against stress 70 in opposite directions longitudinally of the axis of rotation of the propellers, and also against distortion about the axis of the propellers, and driving means for said propellers arranged outside of said space. 75

5. The combination of a propeller blade of aeroform shape and means co-acting therewith entirely along one face thereof and forming a rigid truss to support the blade, compression members of the truss 80 having cross-sections of stream line shape.

6. A propeller having a truss of which the propeller blade forms a part, for supporting the blade against stress in opposite directions longitudinally of the axis of rotation of propeller, the center of support of the blade being forwardly of the center of pressure thereof.

7. A propeller having a blade and truss members on one face of the blade for supporting the same against stress in opposite directions longitudinally of the axis of rotation of propeller, the blade being of aeroform shape, the other exposed parts of the propeller of relatively large cross sections 95 being of stream line shape.

8. A propeller having a blade and supporting means for the blade arranged exteriorly thereof, the center of support of the blade being forwardly of the center of 100 pressure thereof.

9. A propeller having a blade of aeroform shape and supporting means for the blade arranged exteriorly thereof and along one face thereof, the center of support of the 105 blade being forwardly of the center of pressure thereof.

10. A propeller having a blade and supporting means for the blade arranged exteriorly thereof and along one face only thereof, the center of support of the blade being forwardly of the center of pressure 110 thereof.

11. A propeller having supporting means for the propeller blade comprising a rigid 115 truss arranged exteriorly of the blade, the center of support of the blade being forwardly of the center of pressure.

12. The combination of two propellers and means for supporting the same for rotation about a common axis, said propellers being spaced apart along said axis and comprising blades and truss members supporting said blades and arranged entirely within the space between the blades of the respective 120 propellers, the center of support of each blade being forwardly of the center of pressure thereof.

13. The combination of two propellers and means for supporting the same for rotation about a common axis, said propellers being spaced apart along said axis and comprising 5 blades and members supporting said blades and arranged entirely within the space between the blades of the respective pro-

pellers, the center of support of each blade being forwardly of the center of pressure thereof.

10

In testimony whereof I have signed my name to this specification.

PETER COOPER HEWITT.
